UNITED STATES PATENT OFFICE

160,481

SAVINGS BANK

Marie Cuomo, Yonkers, N. Y.

Application February 18, 1950, Serial No. 8,018

Term of patent 7 years

(Cl. D34—11)

To all whom it may concern:

Be it known that I, Marie Cuomo, a citizen of the United States, resident of, city of Yonkers, State of New York, have invented a new, original, and ornamental Design for a Savings Bank, of which the following is the specification, reference being had to the accompanying drawing, forming a part hereof in which:

Fig. 1 is a perspective view of a savings bank, showing my new design.

Fig. 2 is a top view thereof in the direction of line 2—2.

Fig. 3 is a bottom view of said savings bank in the direction of line 3—3 partially omitted for convenience in illustration.

I claim:

The ornamental design for a savings bank, as shown and described.

MARIE CUOMO.
